UNITED STATES PATENT OFFICE.

WILLIAM ROLAND BANKSON, OF PARTRIDGE, KANSAS.

GRAVITY TRAY-CARRIER.

1,168,459.

Specification of Letters Patent. Patented Jan. 18, 1916.

Application filed November 22, 1912. Serial No. 732,981.

To all whom it may concern:

Be it known that I, WILLIAM ROLAND BANKSON, a citizen of the United States, and a resident of Partridge, in the county of 5 Reno and the State of Kansas, have invented certain new and useful Improvements in Gravity Tray-Carriers, of which the following is a specification.

This invention relates to an improved carrier and the principal object of the same is to provide a carrier so constructed that the track may be tilted and the carriage caused to travel from one end of the track to the other.

15 Another object of the invention is to provide improved means for suspending the rails of the track and improved means for tilting the track and holding the rails at the desired incline.

20 Another object of the invention is to provide an improved type of carriage and to so construct the carriage as to have the same strong and durable and not liable to jump the track.

25 Another object of the invention is to provide an improved type of tray, the tray being so constructed that it may be releasably connected with the carriage.

Another object of the invention is to provide 30 an improved type of brake.

This invention is illustrated in the accompanying drawings, wherein—

Figure 1 is a view showing the track in side elevation. Fig. 2 is a view showing the 35 carriage in top plan. Fig. 3 is a view showing the track in end elevation, and Fig. 4 is a view showing the tray in side elevation, a portion of the wall of the tray being broken away.

40 The rails 10 of the track are carried by the hangers 11 which are in their turn carried by the suspending rods 12 pivotally connected with the bell-crank levers 13 and 14. These rails are tapered upwardly in 45 cross section as shown in Fig. 3 in order to provide a good clearance space between the rails and permit the carriage, hereinafter described, to travel freely.

In order to permit the track to be tilted 50 the bell-crank levers are suspended by their pins or axles 15 from the rods 16 which in their turn are carried by the hanger brackets 17 connected with the ceiling or other support 18. A line 19 as shown at the left 55 of Fig. 1 will be connected with each end of

the track, the line being passed over a pulley 20 and having its free end extending to a point where it may be easily grasped by the operator. It is desired to have the bell-crank levers move together and therefore a 60 connecting rod or bar is provided, the rod being pivotally connected with the bell-crank levers and thus causing them to move together. It should be noted that the lower arms of the levers 14 are longer than the 65 arms of levers 13 so that the track will assume the proper incline when tilted.

The car or carriage 22 shown in Fig. 2 is mounted upon the track with the wheels 23 resting upon the rails 10 and travels between the hangers 11 when the track is tilted. This carriage is braced by the diagonal braces 24 which extend from the axles 25 and are crossed upon and connected with the cross bars 26 between the sockets 27. 70 Bars 28 are carried by axles 25 and engage the resilient brake bars or strips 29 when the carriage reaches the ends of the track. One of these brake strips is provided at each 75 end of the track between the end sets of 80 hangers and is connected with rod 21 by the draw line 30 so that when the track is tilted the brake strip at the upper end of the track will be raised out of engagement with the 85 bar 28 and permit the car to travel down the track.

When in use the track is installed where it is desired to use the same and the car is put in place. This device is primarily extended to be used in conveying dishes from 90 a dining room to a kitchen but it is obvious that it could be put to other uses such for instance as for use in a store to carry bundles and change from one point to another. When used in a dining room the dishes will 95 be placed upon the tray 31 and the tray connected with the carriage by inserting the plugs 32 into the sockets 27. These plugs are carried by the block 33 which carries the yokes 34 and it will be readily seen that if desired the plugs can be left in the sockets and the tray removed from the yokes when serving or cleaning the table.

I have therefore provided a device by 100 means of which dishes or other articles can be easily conveyed from one portion of a room to another the dishes being placed upon the tray and the line 19 being drawn to tilt the track and raise the brake strips and release the carriage. It will also be seen that 110

when the car reaches the opposite end of the track its movement will be stopped by the brake strip and thus danger of the dishes being broken will be prevented.

5 Having thus described the invention what is claimed is:—

1. A device of the character described comprising a track including rails, hangers for said rails including bell-crank levers, a 10 draw line connected with each end of said rails, resilient brake strips positioned adjacent each end of said track between certain of said hangers, a bar connecting the bell-crank levers of said hangers, a draw line 15 connected with each end of said bar and with said brake strips, and a carriage mounted upon the rails of said track.

2. A device of the character described including a track comprising hanger brackets, 20 suspending rods connected with said brackets, bell-crank levers connected with said rods, suspending rods connected with said levers, hangers connected with said last mentioned rods, rails connected with said hangers, means for tipping said track, means for 25 causing said bell-crank levers to move in

unison, and brake means operated from said last mentioned means.

3. A device of the character described including a track comprising rails, hangers 30 for said rails including bell-crank levers, the lower arms of said levers increasing in length from the center toward the end portions of said track, means for causing said bell-crank levers to move together, brake 35 means connected with said last mentioned means to cause the brake means to be operated when the track is tilted, and means for tilting said track.

4. A device of the character described 40 comprising a track having rails, a carriage mounted upon said rails, a brake strip carried by said track adjacent the rails thereof, a strip carried by said carriage for engaging said brake strip, means for tilting said track 45 and means for moving said brake strip out of a position to engage said carriage strip when said track is tilted.

WILLIAM ROLAND BANKSON.
